FORMING MECHANISM FOR WEB PRESSES

Application filed November 12, 1930. Serial No. 495,065.

The present invention relates to formers for web presses and has for an object to provide an improved construction which will overcome certain difficulties heretofore encountered in collecting sheets from two formers.

The present method of forming newspapers of standard size is to slit the printed webs medially on the drag roll before running them upon two adjacent formers. Each set of half webs is then run over its former through the nipping rolls and into the folder. Usually, the folder is situated directly under one of the formers and the half webs or sheets coming from the other former must be wrapped 90° about a comparatively small roll and carried across to the folder, where they must be wrapped 90° in the opposite direction about another small roll to lead them vertically into the folder. In passing about these rolls the folds in the sheets wrinkle and crumple, straining the sheets and making register difficult. When running a newspaper of the so-called "tabloid" size, the half webs also are slit medially as they run over the drag roll. In such case although there are no folds in the sheets to wrinkle and crumple, the sheets when making sharp bends about the small guide rolls, tend to slide laterally and to creep upon one another. This tendency is particularly marked in the outside sheets.

An object of the present invention is to overcome the difficulties described above and to provide a construction in which there will be no sharp bends or turns in the sheets as they leave the formers. To this end, I provide a pair of formers each with its individual drag roll and set at such an angle that the sheets will converge and run directly into a common pair of nipping rolls which will lead them into the folder.

It is common practice to stagger the plates on the printing cylinders and compensation is necessary to bring the two half webs into register. My invention has for an object to effect such compensation before the sheets reach the formers rather than after they have left the formers, as is the present practice. To this end, I provide means for slitting each full printed web as it comes from the press

and then pass one set of half webs about compensating rolls before leading said set to the drag roll.

Another object of my invention is to provide means for spreading the two sets of half webs apart tilting them so that they may be led at the proper angles to the two drag rolls.

Other objects and advantages of my invention will appear in the following description of a preferred embodiment and thereafter the novelty and scope of the invention will be pointed out in the claims.

In the accompanying drawings;

Figure 1 is a fragmental and somewhat diagrammatic side elevation of my improved forming mechanism applied to a web press;

Fig. 2 is a fragmental plan view of the same;

Fig. 3 is a front elevation showing the angular disposition of the two formers;

Fig. 4 is a fragmental side elevation looking in the direction of the arrow 4 of Fig. 3; and

Fig. 5 is a fragmental side elevation of the press showing a pair of perfecting units for printing two of the webs shown in Fig. 1.

As best shown in Fig. 3, I provide a pair of drag rolls 10 and 11 mounted in suitable inner and outer bearings 12 and 13 respectively, on the frame 14 of the press. The drag rolls are symmetrically disposed with respect to the press, but are set at a substantial angle to each other. The drag rolls 10 and 11 are interconnected at their adjacent ends by bevel gears 15, while the roll 10 at its outer end carries a miter gear 16 meshing with a miter gear 17 on a drive shaft 18. Leading downward from the drag rolls 10 and 11 are two formers 19 and 20 respectively, and mounted at the lower end of each former are the conventional guiding rollers 21 and nipping rollers 22. The drag rolls and formers are disposed at such an angle that the axial planes X-X and Y-Y will intersect at a central pair of nipping rollers 23. Immediately below the latter are the conventional folding roller 24 and cutting roller 25.

In order to clear the gears 15 and the inner

bearings 12 of the drag rolls, the full width printed sheets as they come from the press must be slit and spread apart and then be led at angles corresponding to those of the two drag rolls. The means for spreading the webs is shown in Figs. 1 and 2. In Fig. 1, I show three full webs 26, 27 and 28 coming from the press. Each web passes through a printing unit such as shown at 27 α and 28 α in Fig. 5, and thence it passes over a slitter roll where it is medially slit. Thus the upper web 26 passes over a slitter roll 29 and is medially slit by a blade 30 into two half webs 26 a and 26 b respectively. Since the printed matter on one half of the web is staggered with respect to that on the other, the half web 26 a is run about a set of compensating rolls so as to bring the two half webs into register before they pass over the drag rolls 10 and 11 respectively. Thus the web 26 a passes under a roll 31, about a roll 32 and thence back under a roll 33. These compensating rolls are all parallel to the slitter roll 29 and are so relatively spaced that after passing about the roll 33 the half web 26 a will be in correct register with the half web 26 b as regards the printing thereon.

The two half-webs must now be spread apart, and to this end the half web 26 a is passed under and over a turning bar 34 and thence under and over a turning bar 35. These bars while horizontally disposed are set at angles of approximately 45 degrees to the medial vertical plane of the press. Similarly, the web 26 b is passed about a pair of turning bars 36 and 37 respectively disposed at corresponding angles on the opposite side of said medial plane. The half webs having been spread by leading them about the turning bars must now be tilted into parallelism with the drag rolls 10 and 11 respectively. Thus from the turning bar 35, the half web 26 a is led over a roll 38 and thence under a roll 39 to the drag roll 10. The rolls 38 and 39 are parallel to the drag roll 10, the roll 39 being immediately adjacent said drag roll. Similarly the half web 26 b is passed over a roll 40 and under a roll 41 to the drag roll 11, the rolls 40 and 41 being parallel to the latter drag roll.

The turning bars 34 and 36 are fixed at their adjacent ends to a bracket 42 carried by a cross bar 43 of the frame of the press, while their opposite ends are secured to brackets carried by a second cross bar 44 of the frame. These turning bars are therefore fixed, but the turning bars 35 and 37 are adjustable to take up slack or, in other words, to maintain uniform tension at opposite margins of the half webs. Another object of adjusting the bars 35 and 37 will appear hereinafter. The bars 35 and 37 are not truly parallel to the bars 34 and 36 respectively, but are set at a slight angle thereto. The inner end 65 of the bar 35 is carried by a bracket 45 on the

bar 43 and the outer end is carried by a bracket 46 secured to the main frame 14 of the press. The bar 35 is secured to said brackets by bolts 47 which pass through transversely elongated slots 48 in the bar so that the position or angular disposition of the bar may be adjusted as required. A similar adjustable mounting is provided for the bar 37.

Like the web 26, the webs 27 and 28 pass over their own individual slitter rolls and are medially slit into half webs 27 a , 27 b and 28 a and 28 b respectively. The half webs 27 a and 28 a pass about compensating rolls similar to the rolls 31, 32 and 33, before passing on to their individual turning bars, while the half webs 27 b and 28 b run direct to the turning bars without passing around compensating rolls. From the turning bars the half web 27 a is led over and under guide rolls 50 and 51 respectively and the half web 28 a is led under and over the guide rolls 52 and 53 respectively. These rolls are parallel to and serve the same purpose as the rolls 38 and 39. The half webs 27 a and 28 a then join the half web 26 a and run over the drag roll 10 as a unit. Similarly the half web 27 b is led over and under guide rolls 54 and 55 to the drag roll 11 and the half web 28 b is led under and over guide rolls 56 and 57 to the same drag roll.

Since the turning bars for the different half webs are at different heights with respect to the drag rolls, compensation must be provided to bring all the half webs of each set into printing register. The guide rollers between the turning bars and the drag rolls are so positioned as to provide such intra-set compensation and a finer regulation may be had by adjusting the turning bars 35 and 37 of half webs 26 a and 26 b and the corresponding turning bars of the other half webs. In order to avoid complication the bearings for the guide rollers 38 to 40 and 50 to 57 inclusive are not shown in the drawings.

If a "tabloid" size of newspaper is being run, each set of half webs is medially slit as it passes about its individual drag roll. To this end slitting blades 58 and 59 are provided as shown in Fig. 3. As explained above, the sets of sheets on passing over the drag rolls 10 and 11, run over the formers 19 and 20 respectively, which are disposed at such angles as to lead the sheets directly into a common pair of nipping rollers 23, whence they run vertically to the folding mechanism.

It will thus be observed that my invention provides for inter-set as well as intra-set compensation of the sheets before they reach the formers, and after the sheets leave the formers they run without bend to the nipping rolls.

The particular embodiment shown in the drawings and described above is to be taken as illustrative and not limitative of my invention, and I reserve the right to make such

changes in form, construction and arrangements of parts as fall within the spirit and scope of the following claims.

I claim:

5. 1. In a web press, a pair of nipping rolls, and a pair of formers converging toward said rolls whereby web portions may run without bending from the formers to said rolls.
10. 2. In a printing press, a pair of formers, and a pair of nipping rolls common to both of said formers, the latter being so relatively disposed that their axial planes will intersect at said nipping rolls.
15. 3. In a printing press, a pair of formers, and a folding mechanism symmetrically spaced from the formers and including a pair of coacting rolls, the formers being so disposed that their axial planes will intersect at said rolls.
20. 4. In a printing press, a pair of formers, a drag roll for each former, a pair of nipping rolls common to both of said formers and disposed at right angles to the drag rolls, the latter being so mutually disposed that each drag roll will be substantially normal to a radius drawn from the center thereof to said nipping rolls.
25. 5. In a web press, a pair of formers, a folding mechanism symmetrically spaced from the formers and including a pair of coacting rolls, the formers being so disposed that their axial planes will intersect at said rolls, and a pair of drag rolls adapted to lead web portions to said formers respectively.
30. 6. In a web press, a pair of formers, a folding mechanism symmetrically spaced from the formers and including a pair of coacting rolls, the formers being so disposed that their axial planes will intersect at said rolls, and means associated with each drag roll for slitting each web portion.
35. 7. In a web press including means for printing a web, means for slitting the printed web into a pair of continuous strips, a former for each strip, a pair of drag rolls for feeding the strips to the formers respectively, the drag rolls being longitudinally spaced apart, and means for spreading the strips and leading them to the drag rolls respectively.
40. 8. In a web press, means for slitting a web into a pair of continuous strips, a former for each strip, a pair of drag rolls for feeding the strips to the formers respectively, the drag rolls being longitudinally spaced apart and mutually inclined, means for spreading the strips apart, and means for tilting the strips respectively to parallelism with the drag rolls.
45. 9. In a web press including means for making printed impressions on a web, a pair of formers mounted in mutually spaced relation, means for slitting the printed web into a pair of continuous strips, means for spreading the strips apart and feeding them to the formers,

the printing on one strip being staggered with respect to that on the other, and compensating means for bringing the two strips into mutual register as regards printing thereon before feeding them upon the formers.

10. In a web press including means for making printed impressions on a web, a pair of formers mounted in mutually spaced relation, means for slitting the printed web into a pair of continuous strips, means for spreading the strips apart and feeding them to the formers, the printing on one strip being staggered with respect to that on the other, compensating means for bringing the two strips into mutual register as regards printing thereon before feeding them upon the formers, and means for slitting each strip medially after said strips have been brought into mutual register.

11. In a web press including means for making printed impressions on a web, means for slitting the printed web into a pair of continuous strips, a former for each strip, a folding mechanism including a pair of nipping rolls, the formers being so disposed that their axial planes will intersect at said nipping rolls, a drag roll for each former with the axis thereof lying normal to the axial plane of the former, means for tilting the strips to parallelism with the drag rolls and leading them thereto, the printing on one strip being staggered with respect to that on the other, and compensating means for bringing the strips into mutual register before they reach the drag rolls.

12. In a web press, means for slitting a web into a pair of strips, a pair of longitudinally spaced and oppositely inclined drag rolls, a pair of turning bars about which each strip is passed to spread the strips to the spacing of the drag rolls, and guide rolls about which the strips are passed before reaching the drag rolls, said guide rolls being set to bring the strips into parallelism with said drag rolls, and means for adjusting the position of one of the turning bars.

13. In a web press, means for slitting a web into a pair of strips, a pair of longitudinally spaced and oppositely inclined drag rolls, a pair of turning bars about which each strip is passed to spread the strips to the spacing of the drag rolls, guide rolls about which the strips are passed before reaching the drag rolls, said guide rolls being set to bring the strips into parallelism with said drag rolls, the printing on one strip being staggered with respect to that on the other, and compensating rolls about which one of the strips is passed before reaching the turning bars so as to bring the printing thereon into register with the printing on the other strip.

14. In a web press, a pair of formers, means for leading a set of web strips to each former, means for adjusting one set of strips

with respect to the other as they are being led to the formers, and means for adjusting each strip with respect to the other strips of its set.

- 5 15. In a web press including means for making printed impressions upon a plurality of webs, means for slitting each web medially to form a right hand strip and a left hand strip, a right hand drag roll common to the
- 10 right hand set of strips, a left hand drag roll common to the left hand set of strips, the drag rolls being longitudinally spaced apart and oppositely inclined, means for spreading the strips in each web and tilting
- 15 each strip to parallelism with its drag roll, and means for effecting relative adjustment of the strips in each set.
16. In a web press including means for making printed impressions upon a plurality of webs, means for slitting each web medially to form a right hand strip and a left hand strip, a right hand drag roll common to the right hand set of strips, a left hand drag roll common to the left hand set
- 20 of strips, the drag rolls being longitudinally spaced apart and oppositely inclined, means for spreading the strips in each set and tilting each strip to parallelism with its drag roll, the printing on the strips in one set being
- 25 staggered with respect to that on the strips of the other set, and compensating means for each strip of one set adapted to bring it into printing register with its companion strip of the other set.
- 30 17. In a web press including means for making printed impressions upon a plurality of webs, means for slitting each web medially to form a right hand strip and a left hand strip, a right hand drag roll common
- 35 to the right hand set of strips, a left hand drag roll common to the left hand set of strips, the drag rolls being longitudinally spaced apart and oppositely inclined, means for spreading the strips in each set and tilting each strip to parallelism with its drag roll, the printing on the strips in one set being staggered with respect to that on the strips of the other set, compensating means for each strip of one set adapted to bring
- 40 it into printing register with its companion strip of the other set, and means for effecting relative adjustment of the strips in each set.
- 45 18. In a web press including means for making printed impressions upon a plurality of webs, means for slitting each web medially to form a right hand strip and a left hand strip, a right hand drag roll common to the right hand set of strips, a left hand drag roll common to the left hand set of strips, the drag rolls being longitudinally spaced apart and oppositely inclined, means for spreading the strips in each set and tilting each strip to parallelism with its drag roll, the printing on the strips in one set being staggered with respect to that on the strips of the other set, compensating means for each strip of one set adapted to bring
- 50 it into printing register with its companion strip of the other set, and means for effecting relative adjustment of the strips in each set.

In testimony whereof, I have signed this specification.

55 HENRY A. WISE WOOD.
